UNITED STATES PATENT OFFICE.

EZRA W. VANDUZEN, OF CINCINNATI, OHIO.

IMPROVEMENT IN WATER-GAUGES FOR STEAM-BOILERS.

Specification forming part of Letters Patent No. 123,751, dated February 13, 1872.

I, EZRA W. VANDUZEN, of Cincinnati, Hamilton county, Ohio, have invented certain Improvements in Water-Gauges for Steam-Boilers, of which the following is a specification:

This invention relates to that class of gauges which serve to indicate the water-level by means of a pointer or hand adapted to revolve in front of a suitable dial, the pointer being operated by a stem or rod, which, after passing into the boiler, is bent rectangularly, and provided with a float; and the improvements consist in imparting a spiral or twisted form to the inner section of the stem, in order that the rotation of said stem may keep the inclosing-tube free of sediment or other obstructions; second, in a peculiar form of support for the inner end of the float-rod.

Figure 1 is a horizontal section through a water-gauge embodying my improvements. Figs. 2 and 3 are enlarged transverse sections taken, respectively, at the lines X X and Y Y; and Fig. 4 is an elevation of that part of the apparatus which is situated within the boiler, the boiler-head being shown in section.

A is the customary wrought-iron pipe or inclosing-tube, which passes horizontally into the boiler-head L, and which is attached thereto by customary nuts B B'. C is the coupling by which the outer end of the tube A is screwed fast to the hub D upon the rear of the dial E.

The float-rod F and pointer-stem G are two distinct and separate pieces or sections, having independent longitudinal movement, but vibrating always in unison by reason of the outer end of the stem having a non-circular socket, f, that incloses a corresponding arbor, g, on the pointer-stem, as seen in Fig. 3. I is an India-rubber "plug" that presses permanently and immovably against a seat, d, so as to effectually prevent the passage of steam and water through the channel which is pro-

vided in the hub for the reception of the pointer-stem G. The "plug" I has preferably the conoidal form represented, and, being always out of contact with the sides of the chamber within which it is located, it is free to twist or bend at every vibration of the stem without being dislodged from its seat d. The end pressure of the plug I may be assisted by a spiral spring, H, in the socket f. A prolongation or arm, K, from the inner end of tube A, terminates with an eye, k, that incloses and supports the inner end of the float-rod.

In order to enable the float-rod by its vibrations to dislodge or remove any sediment or incrustation from the interior of the tube A, I prefer to make said rod of a twisted or spiral shape, as represented.

The open arm K is preferable to the ordinary prolongation of the tube itself within the boiler, such prolongation being liable to become choked with incrustations and sediment, and, by obstructing the free rotation of the float-rod, imparting false indications, and thus causing a device designed for safety to become an element of danger.

Claims.

I claim as my invention—

1. The float-rod F, having the twisted or spiral form represented, for the purpose specified.
2. The arm K, having the eye k, for the support of the float-rod, the said arm projecting from the inner end of the tube A, and supported therewith, as shown and described, for the purposes set forth.

In testimony of which invention I hereunto set my hand.

EZRA W. VANDUZEN.
